UNITED STATES PATENT OFFICE

GUSTAV A. GRAB, OF PORTLAND, OREGON, ASSIGNOR TO WILLAMETTE IRON AND STEEL WORKS, OF PORTLAND, OREGON

TRAVERSING HOIST

Application filed March 1, 1927. Serial No. 171,748.

This invention relates generally to traversing hoists, and particularly to the self-propelled type designed for surface operation and especially intended for the handling of objects by straddling same and then picking them up bodily, with special reference to the handling of piled lumber.

The first object of this invention is to provide an exceedingly simple and efficient traversing hoist having combined swinging and lifting arms by means of which the load can be engaged and suspended.

The second object is to provide a special type of lifting mechanism employing a self-opposed horizontal lifting screw.

The third object is to provide a positive upward and downward feed for the lifting mechanism.

The fourth object is to so construct the hoist that it can lift its wheels bodily off from the ground for the purpose of extracting same from ruts, replacing the tires, or working on the wheels.

The fifth object is to employ one pair of opposed lifting frames of a flexible nature which will permit the proper engagement with a load and the ultimate alinement of the load with the hoist before the load is lifted.

The sixth object is to secure great rigidity of the parts while carrying the load and flexibility in the load lifting parts while in the lowermost portion of their travel.

The seventh object is to provide a hoist having its lifting members possessed of longitudinal rigidity and lateral flexibility.

The eighth object is to so construct the hoist that it will be impossible to operate the lifting mechanism until the load is properly engaged, or in an innermost position.

The ninth object is to provide a power driven lifting mechanism and a manually operated load engaging mechanism within easy control of the operator, making it possible for one operator to easily handle the machine and pick up or place a load in any desired position.

The tenth object is to provide equalizing means for the connections which urge the ex-

treme ends of the lifting angles toward the load.

The eleventh object is to provide a yielding connection between the lifting mechanism and the load supporting angle in order that slight obstacles in the road bed can be overcome by the bodily lifting of one corner of the load supporting frame without the actual raising of the hoist itself or subjecting same to unusual shocks.

The twelfth object is to provide a hoist whose load-supporting and lifting members will not be rendered inoperative due to continued rough usage and shocks imposed thereon by the encountering of obstructions and the quick starting and stopping of the load.

These, and other objects, will become more apparent from the specification following as illustrated in the accompanying drawings, in which:

Figure 1 is a side elevation of the traversing hoist. Figure 2 is a longitudinal section through the double end thrust bearing of the lifting screw. Figure 3 is a plan showing the lifting device and equalizing parts. Figure 4 is a vertical section taken along the line 4-4 in Figure 3. Figure 5 is a horizontal section taken along the line 5-5 in Figure 1. Figure 6 is a vertical section taken along the line 6-6 in Figure 3. Figure 7 is a horizontal section taken along the line 7-7 in Figure 6. Figure 8 is a transverse section taken along the line 8-8 in Figure 1 showing the hoist straddling a load preparatory to engaging same. Figure 9 is a view similar to Figure 8 showing the lifting dog moved into position against the load ready to start the lifting action. Figure 10 is a view similar to Figure 9 showing the load lifted. Figure 11 is a perspective view of the cross head guide. Figure 12 is a horizontal section taken along the line 12-12 in Figure 1.

Similar numbers of reference refer to similar parts throughout the several views.

Referring in detail to the drawings, there is illustrated a traversing hoist including the wheels 10, steering spindles 11, spindle brackets 12 and longitudinal frames 13, 14 and 15 which are joined by the cross frames 16, 17, 18 and 19. The outline of an engine

20 and operator's seat 21 are also indicated.

On each side of the hoist, near each end thereof between its wheel members 10, are secured the spaced upright guides 22 consisting of inturned angles which are secured to the members 13, 14 and 15 by means of the clips 23. To the outer sides of the members 22, extending between the members 13 and 14, are the out-turned angles 24 which act as locks preventing the release of the load before it is otherwise supported.

Mounted between the inner edges of the members 22 is a cross head 25 provided with an elongated vertical slot 26. The cross head 25 is attached by means of a link 27 to the lower end 28 of a bell crank lever 29, which is pivotally mounted on the bracket 30 which is attached to an upright frame member 31. The upper end of the bell crank lever 29 is jointed by a link 32 to a nut 33 on the threaded end 34 of the shaft 35 provided with a double thrust bearing 36 which may be combined in one, or otherwise positioned as seems best. The shaft 35 is supported in bearings 37 on the frame 13.

In the slot 26 is placed a pin 38 which pivotally supports one end of the load supporting frame, which consists of a pair of upright angles 39 reinforced by the angles 40 and attached by the vertical pivots 41 to the load supporting angle 42 by means of an interposed bracket 43, whose inner side 44 is high at its middle portion to permit angular movement between the load supporting angle 42 and its attached load supporting frames.

It will be understood that the brace members 17 provide only longitudinal rigidity but are laterally flexible, at least sufficiently so to permit the ends of the load lifting frames to move laterally with relation to each other—that is, the rearward end of a hoist frame can move laterally independently of its forward end, and vice versa. Obviously, if the sides 44 were made straight—that is, parallel with the members 42, it would either fail to back up the side of the member 42 or would otherwise clamp it rigidly to the uprights 39, in which case lateral flexibility would be eliminated, which is one of the reasons existing types of hoists employ four separate shoes, or else employ laterally rigid lead lifting shoes.

It will be understood that a similar arrangement of parts is positioned at each end of the load supporting angle and that there is a load supporting angle on each side of the hoist, also that the load supporting angles face each other for the purpose of engaging the under side of the bolster ends 45 upon which lumber 46, or other objects, are piled.

On top of the frames 17 and 18 are secured the plates 47 upon each of which is mounted a lever 48 on the pivot 49. On the end of each

lever 48 is mounted a floating lever 50 to whose members 51 and 52 are attached the connecting rods 53 which extend laterally to the pivotal connections 54 which, in turn, carry the rollers 55 operating in a tee slot in the member 56 secured to the upper end of the load supporting frame. Similar parts 47 to 56 connect transversely the other ends of the opposite frames.

The shafts 35 are provided with right and left threads at their opposite ends and the two shafts are provided with the sprockets 57 which are connected by the chains 58 to the sprockets 59 from the clutch power shaft 60 which is provided with an upright clutch control lever 61 in whose path is placed a sprung-urged pin 62 which is normally held out of the path of the lever 61 by its spring. On the longitudinal frame member 63 is mounted an upright shaft 64 to which is attached a two armed lever 65 from whose arms extend the connecting rods 66 to the floating lever 50. The shaft 64 is mounted in a longitudinal slot 67 permitting same to move forward or backward to equalize the pulls on the forward and rearward floating levers 50, each of which itself equalizes the pulls of the laterally extending rods 53.

On the shaft 64 is secured a cam 68 adapted to engage the pin 62 when the lever 69 is pushed away from the operator, causing the end of the pin 62 to intercept the clutch lever 61. In other words—the lever 69, whose movement away from the operator causes the load supporting angles to spread away from the load, prevents the clutch lever 61, which controls the application of power to the lifting mechanism, from being operated; but when the lever 69 is pulled toward the operator and the load is engaged it is possible to move the clutch lever 61 to an operating position.

In other words—if the operator wishes to pick up a load he must first take hold of it by means of the shoes 42 which he must place under the ends 45 of the bolsters. To do this the operator pulls the lever 69 toward him—that is, away from the position shown in Figure 3, which will cause the push rods 53 to move outwardly and the lower ends of the load lifting frames to spring inwardly. Obviously, this will permit the pin 62 to clear the clutch control lever 61 and allow the operation of the lifting mechanism. Since the cam 68 must free the pin 62 it follows that if for any reason the shoes 42 do not pass under the ends 45 of the bolsters then the lever 69 cannot be operated sufficiently far toward the driver to permit an attempt at lifting the load.

It is preferable to provide a guide 70 for the upper side of each rod 53, since these would otherwise move upwardly when the load was being raised causing a change in

their length and a consequent lateral movement of the load supporting angles 42.

No attempt has been made to elaborate on details not intimately connected with this invention, and it is not intended that the precise forms of elements herein illustrated are essential to the operativeness of the hoist. It is a well known fact that many forms of traversing hoists have been constructed in the past in which four independent load supporting arms were swung beneath the frames of such machines. In many instances these were rigidly connected together by mechanical operating means, and in other instances they have been made separately operable and yielding.

In this instance, however, a load supporting angle is placed on each side of the load, and while this angle is flexible or yielding as to angularity for the purpose of adapting itself to the relation between the hoist and a load about to be picked up, these angles are not capable of endwise movement with relation to the hoist itself. In other words—any jars or impacts which would tend to move the angles 42 longitudinally are transferred directly to the cross heads which are rigidly guided in the frame of the hoist, and the load supporting frames themselves are rigidly braced longitudinally with relation to the load supporting angles, by means of the braces 71 which are relatively thin and flexible.

It can now be seen that should the hoist be run straddling over the top of a pile of lumber, although not exactly in line with same (as is most often the case) that the operator having stopped the hoist near the middle of the pile now pulls the lever 69 toward him, which tends to draw the laterally opposed corners of the load supporting angle toward each other. Obviously, if the load is out of line with the hoist, one corner of the angle will engage the bolster end 45 before its mates. At this point the lateral equalization of the parts occurs at the end of the hoist, first to engage the load, and the same operation then transpires at the opposite end of the hoist; and added to this equalization feature is the fore and aft equalization through the rod 66, which makes it certain that the load supporting angles will assume their proper relation to the bolsters which support the load, as, for example, as shown in Figure 9.

It will be noted in Figure 8 that the point 72 of the load supporting frame does not bear against the angle 24 at this time, but is below the end of same and is above the pin 38, which makes it possible for the angle 42 to swing outwardly between the wheels 10. However, when the angle 42 has been moved to the position shown in Figure 9 by means of the lever 69 and the pin 62, which locks the clutch lever 61, is therefore withdrawn,

it is now possible to raise the load to the position shown in Figure 10. In which case the point 72 is moved upwardly and the entire upper end of the load supporting frame below the point 72 bears against the angle 24, making it impossible for same to spread at its lower ends sufficiently to allow the load to escape and fall to the ground.

Again, it will be noted in Figure 9 that if, for any reason such as irregularities in the roadway or other factor, one corner of the load supporting member should be raised, that such action will be possible without serious consequences, owing to the slot 26 which permits the pin 38 to rise therein without exerting a lifting action on the frame itself, at least for a predetermined distance, which is sufficient to take care of all ordinary contingencies.

It is preferable in some instances to provide a guide 73 for the upper sides of the nuts 33 to take care of the upward thrusts against the shaft 35 between its bearings 37. In Figure 2 is illustrated a double end thrust bearing which is contained within the housing 74.

It will be noted that the shaft 35 is normally always in tension and would not be in compression unless there should be a binding between the cross heads and their guides, or the wheels were being lifted up by placing a bolster under the load supporting angles for the purpose previously mentioned, in which case the shaft 35 would be placed in compression.

While the members 73 are useful in providing lateral reinforcement for the shaft 35, their main function is to prevent the rotation of the nuts 33 on the threaded portion of the shaft 35.

It will be understood that the object in preventing the occurrence of any lifting action before the load supporting frames are in their proper position—that is, either engaging a load or in their innermost positions, is because even if it were possible to apply the lifting action when the lower ends of the load supporting frames were not in their innermost position, such lifting action would result in a gradual forcing in of the load engaging members due to the fact that the point 72 will ride upon the members 24. This would result either in splitting the object between the load supports or seriously damaging the operating mechanism, and in all probability it would be the latter of these two conditions.

It can be readily seen that, due to various conditions such as depressions in the ground, poorly piled loads, trash or other obstacles, may prevent the load supporting angles from passing under the ends 45 of all of the bolsters. Especially at night is the operator unable to observe such conditions closely; and the result is that if he undertakes to lift an improperly engaged load the engaging members merely claw up the sides of the pile and

tend to further disrupt same, or else seriously injure the mechanism, as above stated.

It is for this purpose that there is provided the clutch lever intercepting pin 62 which 5 renders it a physical impossibility to lift the load unless all of the bolsters are properly engaged.

I claim:

1. In a traversing hoist, the combination of 10 a wheeled straddle frame having vertical guides on the sides thereof; a cross head in each of said guides; a laterally flexible and longitudinally rigid load supporting frame at each side of said frame hingedly mounted at 15 its forward and rearward ends on said cross heads; and a load supporting angle attached to the lower end of said load supporting frame by means of pivotal connections adapted to permit independent lateral movement of the forward and rearward ends of 20 said frame.
2. In a traversing hoist, the combination of 25 a wheeled straddle frame with a pair of spaced vertical slides at each side of said frame; a cross head in each slide; a longitudinal rigid frame hinged near the middle of its height to said cross heads, the lower ends of said frame having a load supporting angle attached thereto by means of vertical 30 pivots adapted to permit independent lateral movement of the ends of said frame; and means incorporated in said slide for preventing outward swinging of the lower end of said frame when in a raised position.
3. In a traversing hoist the combination of 35 a wheeled frame having a vertical slide near each upper corner thereof, a cross-head mounted in each slide said cross-heads having means for positively operating same in unison upwardly and downwardly, each slide having an extension guide thereon, a longitudinal load supporting frame along each side of 40 said hoist hinged to said cross-heads, a longitudinal foot extending across the lower ends 45 of each load supporting frame, said load supporting frame having portions thereof above its hinge adapted to engage said extension guide when raised in a manner to prevent an outward movement of the foot 50 of said load supporting frame, said upwardly extending portion thereof clearing said extension guide in a manner to permit the outward swinging of said load supporting frame in a lowered position.
4. In a traversing hoist the combination of 55 two pairs of laterally disposed spaced vertical guides arranged in tandem with a cross-head mounted in each of said guides having means for positively operating same in both 60 vertical directions, a unitary load supporting frame between each lateral pair of cross-heads consisting of two upright end members having laterally flexible longitudinal braces between same, a longitudinal load 65 supporting angle uniting the lower ends of

each load supporting frame, said end members being adapted to permit lateral flexibility of movement of said load supporting angle, said uprights having hinged connections to said cross-heads adapted to permit a limited amount of free upward movement to either end of a load supporting frame, means for locking said load supporting frame against outwardly swinging movement as soon as it begins to rise, and means for preventing the operation of said cross-heads unless both of said load lifting frames are in a load engaging position along their entire lengths. 70

5. In a traversing hoist, a load lifting mechanism consisting of a horizontal threaded shaft having a pair of nuts mounted thereon, a bell crank lever mounted under each nut, a cross-head under each bell crank lever, connecting links between each nut and cross-head and its bell crank lever, and means for suspending a load from said cross-heads. 75

6. In a traversing hoist, a load lifting mechanism consisting of a horizontal shaft having opposite threads formed thereon; a nut on each of said opposite threads; a bell crank lever under each of said nuts; a vertically slideable cross head under each of said bell crank levers; link means between each of said bell crank levers and its associated cross head and operating nut; and means for rotating said shaft. 80

7. In a traversing hoist, a load lifting mechanism consisting of longitudinally spaced vertical guides attachable to the hoist; a cross head mounted in each guide; a unitary load supporting frame hinged near the middle of its height to said cross heads, said frame having longitudinal rigidity over its entire area and lateral flexibility at the lower load engaging end thereof, the upwardly extending ends of said frame having equalized lateral thrust rods attached thereto for the purpose of swinging the load engaging end of said frame inwardly; a power driven horizontal shaft mounted above said cross heads having opposite threads formed thereon over the two cross heads, each of said threaded portions having a nut thereon provided with operating bell crank levers and links whereby a rotative movement of said shaft which moves said nuts toward each other will raise said cross heads. 100

8. In a traversing hoist, a load lifting mechanism consisting of longitudinal spaced vertical guides attachable to the hoist; a cross head mounted in each guide; a unitary load supporting frame hinged near the middle of its height to said cross heads, said frame having longitudinal rigidity over its 105 entire area and lateral flexibility at the lower load engaging end thereof, the upwardly extending ends of said frame having equalized lateral thrust rods attached thereto for the purpose of swinging the load engaging 110

end of said frame inwardly; a power driven horizontal shaft mounted above said cross heads having opposite threads formed thereon over the two cross heads, each of said threaded portions having a nut thereon provided with operating bell crank levers and links whereby a rotative movement of said shaft which moves said nuts toward each other will raise said cross heads; and clutch means between said shaft and its source of power having means for locking same out of engagement when said load supporting frame is not in a complete load engaging position.

9. In a traversing hoist, the combination of a wheeled frame having two pairs of vertical guides attached thereto in parallel longitudinal planes; a cross head in each guide; a unitary frame having longitudinal rigidity and lateral flexibility hinged across both of said cross heads above the middle of the frame height; a horizontal self-opposed screw mounted on said frame above said cross heads; a nut on each end of said screw, a bell crank lever under each nut, link means for operatively connecting each bell crank lever to its cross head; and equalized connecting rod means for moving the lower corners of said load supporting frame into a load engaging position, said equalized means forming a lock for preventing the operation of said cross heads when said load supporting means is not operatively engaging its load or occupying innermost positions.

10. In a traversing hoist, a load lifting mechanism consisting of a wheeled frame in combination with two pairs of transversely opposed vertical slides mounted on said frame, a cross-head in each of said slides, a longitudinal load lifting frame hinged along each side of said hoist to the cross-heads above same, each of said load lifting frames having their upper ends projecting above their points of hinging, floating levers between the forward and rearward upwardly projecting ends of said load lifting frames, bell crank levers mounted on said floating levers, push rods between said bell crank levers and the forwardly projecting ends of said load lifting frames, a second floating lever between said first mentioned floating levers having connecting rods between same and said bell crank levers, lever means for actuating said second mentioned floating lever, a cam operated by said second mentioned floating lever, and means actuated by said cam for preventing vertical movement of said cross-heads when said load lifting frame is not in a load engaging position.

GUSTAV A. GRAB.
